UNITED STATES PATENT OFFICE.

JOSEPH JOHN HERZOG AND WALTER MARTIN MEDLOCK, OF MOBILE, ALABAMA.

CENTRIFUGAL GOVERNOR.

1,275,026.

Specification of Letters Patent.

Patented Aug. 6, 1918.

Application filed April 2, 1917. Serial No. 159,319.

To all whom it may concern:

Be it known that we, JOSEPH JOHN HERZOG and WALTER MARTIN MEDLOCK, citizens of the United States, and residents of Mobile, in the county of Mobile and State of Alabama, have invented certain new and useful Improvements in Centrifugal Governors, of which the following is a specification.

10 Our invention relates to improvements in centrifugal governors, and consists in the combinations, constructions and arrangements herein described and claimed.

This application is a continuation in part 15 of a prior application, Serial No. 63216, filed Nov. 24, 1915, said application being for an automatic spark timer for internal combustion engines, of which the governor, which forms the subject of the present invention, was a part.

An object of the invention is to provide a new form of centrifugal governor in which the force exerted by the centrifugal members may be transmitted to a movable part 25 in almost any ratio, depending upon the construction of certain cam portions of the centrifugal members.

A further object of our invention is to provide a centrifugal governor which is 30 more readily controlled and whose action is more steady than governors of the existing types.

Other objects and advantages will appear in the following specification and the novel 35 features of the invention will be particularly pointed out in the appended claims.

Our invention is illustrated in the accompanying drawing, in which:

Figure 1 is a perspective view showing 40 one embodiment of the invention.

Fig. 2 is a plan view of the centrifugal governor.

Fig. 3 is a section on the line 3-3 of Fig. 2, and

Fig. 4 is a plan view of a modified form 45 of the device.

Referring now particularly to Fig. 4, we have shown therein a form of the device which was disclosed in my prior application 50 aforesaid.

The other figures of the drawing represent a modified form, but which is substantially the same as that shown in Fig. 4.

In Fig. 4, 5 represents a casing which 55 encloses a plate 12. Carried by the plate are the pivot pins 21 and 22. Upon the former is pivotally mounted a centrifugal member 23, while a similar centrifugal member 24 is mounted on the pin 22. Each of these centrifugal members 23 and 24 is provided with 60 a cam surface arranged to engage the bar or lever 15. The contours of these cam surfaces are precisely the same, and a description of one will suffice for both. The cam surface of the centrifugal member 23 is 65 curved, as shown at 23^a on a curve which is so designed as to move the lever 15 a predetermined distance for a given movement of the centrifugal member 23. Similarly, the centrifugal member 24 is curved at the 70 end which engages the lever 15 for similar movement. Each of the centrifugal members 23 and 24 is held in close engagement with the lever 15, by means of springs such as those shown at 25, one end being attached to the centrifugal member and the 75 other to the lever.

In this particular instance, the lever 15 is connected with a distributing device or make and break wheel 18, for advancing or 80 retarding the latter.

The preferred form of the device is set forth in Figs. 1, 2 and 3, in which 1 is a shaft having a gear 2, or other suitable driving mechanism. Secured to the shaft is a 85 plate 3, having pins 4 and 6, upon which the centrifugal members 7 and 8 respectively, are pivoted.

The plate 3 is secured to the shaft by means of a set screw 9 or in any other suitable manner, see Fig. 3. In this particular instance the shaft 1 has a reduced extension 1^x upon which is mounted a rotatable sleeve 10, having secured to it a collar 11, which is provided with extensions 12. The sleeve 90 10 is provided with laterally extending integral portions 13. The members 10 to 13, inclusive, constitute a lever of the first class. The centrifugal members 7 and 8 are provided with cam surfaces 7^a and 8^a, respec- 100

tively, which are arranged to engage the extensions 13. Springs 25 are connected to the ends of the extensions 13 and to the posts or pins 4 and 6, respectively. The operation 5 of this form of the device is the same as that set forth in Fig. 4. The speed of the shaft 1 will cause the centrifugal members to swing downwardly on their pivots 4 and 6, and the cam surfaces 7^a and 8^a will bear on 10 the extensions 13, which it will be observed are equivalent to the lever 15 in Fig. 4. This will turn the sleeve 10 and the turning of the latter may operate any movable part such as regulating a valve, advancing the 15 sparking mechanism in an internal combustion engine or for any purpose where a governor may be used.

A device of this kind has a very decided advantage over the ordinary governor. The 20 latter generally has heavy springs which are necessary to offer the desired resistance to the centrifugal members at high speed. The action of the ordinary governor is like an attempt to move a heavy block on a smooth 25 surface, with a free hand for a small distance. The inertia of the block tends to make it start hard, but when it is once started it will move suddenly and without control. On the other hand with the present 30 governor the centrifugal members are always under control due to the fact that the centrifugal members are acting on opposite sides of the central pivot of a common lever.

Moreover, applicants' device is exceedingly sensitive. It may be here stated that 35 the trouble with governors, especially those used in connection with automatic spark timers, is that at low speed they will not move in proportion to the speed, while at 40 high speed the movement is greater due to the momentum which the centrifugal devices have acquired. Now, in the present device, the cam has its greatest leverage while the lever arm is longest, thus, there is comparably great force acting on a long arm so 45 that the starting of the centrifugal member when the speed is low, is easily accomplished. Now, as the speed gets greater, the point of engagement of the centrifugal device with 50 the lever shifts toward the pivot of the lever; that is to say, the lever arm of the centrifugal device then becomes longer, while the lever arm of the lever itself is shorter. The cam curve, of course, can be 55 made so as to cause just the movement which is necessary in shifting the fast lever in proportion to the speed of the vehicle.

The fact that the centrifugal devices respond immediately to the increased speed 60 and that they are always under control, permits the governor to be used in connection with speedometers or other devices requiring extreme accuracy.

We claim:

1. In a governor, a shaft, a plate rigidly 65 secured to said shaft, said shaft extending through the center of the plate, a lever pivotally mounted on said shaft, a pair of centrifugal members pivotally mounted on said plate, each of said centrifugal members having a cam surface arranged to engage one side of said lever near the point of engagement shifting toward the pivotal point of the lever as the speed increases and spring connections between said lever and 70 said plate for returning said lever to its normal position of rest.

2. In a governor, a shaft, a plate rigidly secured to said shaft, said shaft extending through the center of the plate, a lever 80 pivotally mounted on said shaft, a pair of centrifugal members pivotally mounted on said plate, each of said centrifugal members having a cam surface arranged to engage one side of said lever near the end thereof, the 85 point of engagement shifting toward the pivotal point of the lever and away from the pivotal point of the cam as the speed increases, and spring connections between the said lever and said plate for returning 90 said lever to its normal position of rest.

3. A centrifugal governor comprising a shaft, a circular plate rigidly mounted upon said shaft at the center of the plate, said circular plate having pins projecting 95 from one side thereof, a pair of centrifugal members pivotally mounted on said pins, a lever pivotally mounted on the shaft in close proximity to said plate, said centrifugal members having cam surfaces arranged to engage the lever at points near 100 the opposite ends, the point of engagement shifting toward the pivotal point of the lever and away from the pivotal point of the cam as the speed increases, a sleeve connected with said lever for rotation on said shaft, extensions rigidly carried by said sleeve on opposite sides of the shaft, and a spring connected with the pivot pin of each 105 of said centrifugal devices, and having 110 connection with the extensions on said sleeve.

4. In a governor, a shaft, a plate rigidly secured to said shaft, said shaft extending through the center of the plate, a lever 115 pivotally mounted on said shaft, a pair of centrifugal members pivotally mounted on said plate, each of said centrifugal members having a cam surface arranged to engage a side of said lever near the end thereof, the 120 point of engagement shifting toward the pivotal point of the lever as the speed increases, and spring means for returning the lever to its normal position of rest.

5. In a governor, a shaft, a plate rigidly 125 secured to said shaft, said shaft extending

through the center of the plate, a lever pivotally mounted on said shaft, a pair of centrifugal members pivotally mounted on said plate, each of said centrifugal members 5 having a cam surface arranged to engage a side of said lever near the end thereof, the point of engagement shifting toward the pivotal point of the lever as the speed in-

creases, and means for returning the lever to its normal position of rest.

Mobile, Ala., March 24th., 1917.
